UNITED STATES PATENT OFFICE.

JOHN C. RAMSDEN, OF REDGATE, GREAT BRITAIN.

APPARATUS FOR HARDENING AND TEMPERING WIRE.

SPECIFICATION forming part of Letters Patent No. 231,848, dated August 31, 1880.

Application filed January 19, 1880. Patented in England April 2, 1879.

To all whom it may concern:

Be it known that I, JOHN CARTER RAMSDEN, a subject of the Queen of Great Britain and Ireland, and a resident of Redgate, in the parish of Bassenthwaite, in the county of Cumberland, England, have invented new and useful Improvements in Apparatus for Hardening and Tempering Wire, for which I have obtained British Letters Patent No. 1,315, dated April 2, 1879, and of which the following is a specification.

The object of my invention is to construct an apparatus for the rapid and effective hardening and tempering of steel wire; and this object I attain in the manner which I will now proceed to describe, reference being had to the accompanying drawings, in which—

Figure 1 is a longitudinal vertical section of the apparatus; Fig. 2, a plan view; Fig. 3, an end view of the hardening furnace; Fig. 4, a transverse section of the same, and Fig. 5 a transverse section of the tempering-bath.

A is a tubular retort or chamber, which is mounted upon supports *a a*, and through which the wire is passed after leaving the reel or reels G. This retort, which may be circular in section or oval, as shown in Fig. 4, is provided with a horizontal partition, N, in the center the length of the chamber, there being openings 30 on each side of the partition, as shown. Along one side of the retort, below the partition N, are a number of openings, y, opposite each of which are two nozzles, O and P, each provided with a cock, Fig. 4.

The pipes carrying the lower nozzles, O, are in communication with a vessel or cistern containing a quantity of volatile hydrocarbon, while the pipes carrying the nozzles P communicate with a boiler or steam-generator, so that when the two cocks are opened the force of the steam passing over the lower nozzle exhausts the air contained in the lower pipe and causes the volatile hydrocarbon to rise therein and be blown into the chamber R, 45 against the partition N, in the finest spray, and when lighted the flame passes along the under side of the partition and up through the openings on each side, into the chamber above the partition, through which the wire 50 passes, and is heated thereby.

The wires to be heated pass through suitable

openings in the ends of the retort and through adjoining guides F F, such wires being introduced into the retort in the first place through a longitudinal slot, L, in the top thereof. This opening is closed by a lid, L', which is carried by arms *l*, secured to the shaft K, the latter being adapted to suitable bearings in the frame. 55

The vertical slots in the ends of the retorts are closed by gates E, which are pivoted to arms *e*, also secured to the shaft K. The upper ends of these gates are provided with slots *e'*, into which fit pins *f*, on the upper ends of the guides F F, so that when the shaft K 65 is turned so as to raise the lid L' the gates E will at the same time be thrown back to the position shown by dotted lines in Fig. 3. The products of combustion from the retort pass out through a chimney, x, at one end, above 70 the partition, and on the opposite side of the retort from the nozzles O P.

The wire, as it is drawn off the reel or reels G, is heated as it passes in the direction of the arrow through the retort, sufficient space 75 being left below the gates E E for the passage of the wire.

When the wire thus heated leaves the retort it passes over an inclined trough, S, down which flows a stream of oil in the opposite 80 direction. This stream of oil is supplied continuously from the pipe T, which communicates with an elevated reservoir. The oil, after leaving the inclined trough S, flows over the tray beneath and thence into the trough T', 85 whence it is pumped back again into the elevated reservoir.

The upper end of the trough S is provided with a pivoted gate, *s*, beneath which the wire thus hardened thence passes into a pan, U, 90 containing a bath of linseed-oil, mercury, or lead, heated by means of a fire, U', to the temperature required to give the wire the requisite degree of temper. The wire is depressed into this bath of oil by pendent arms 95 *d*, secured to the pivoted cover D of the tempering-box. The products of combustion from the fire pass out through the chimney *w*. The wire is then drawn onto the ordinary reels G', which are arranged in any desired position, and have a positive motion imparted to them by any suitable means. 100

I claim as my invention—

1. In an apparatus for hardening wire, the combination of a wire-heating retort provided with a central partition having openings on opposite sides thereof with nozzles or burners for introducing combustible material into the retort below the partition, substantially as set forth.
2. A wire-heating retort provided with a longitudinal slot, through which the wire to be treated may be introduced into the retort, substantially as described.
3. The wire-heating retort provided with a longitudinal slot and removable lid, as and for the purpose specified.
4. The combination of the retort having a longitudinal slot with a shaft carrying a lid

adapted to said slot and gates adapted to the slotted ends of the retort, all substantially as set forth. ²⁰

5. The combination of the tempering-pan with the pivoted cover carrying the pendent arms, as and for the purpose described.

6. The combination of the tempering-box containing the bath-pan with the fire-place ²⁵ immediately below the same.

In testimony whereof I have signed my name to this specification in the presence of two subscribing witnesses.

JOHN CARTER RAMSDEN.
